UNITED STATES PATENT OFFICE.

THOMAS G. SAXTON, OF LEXINGTON, KENTUCKY, ASSIGNOR TO EMELIUS M. MCKEE, OF LEXINGTON, KENTUCKY.

PISTON-PACKING.

1,241,770.

Specification of Letters Patent.

Patented Oct. 2, 1917.

Application filed June 6, 1916. Serial No. 101,917.

To all whom it may concern:

Be it known that I, THOMAS G. SAXTON, a citizen of the United States, residing at Lexington, in the county of Fayette and State of Kentucky, have invented certain new and useful Improvements in Piston-Packing; and I do hereby declare the following to be a full, clear, and exact description of the invention, such as will enable others skilled in the art to which it appertains to make and use the same.

This invention relates to pistons or piston packing, and more particularly to pistons of that class or type in which a metallic packing is used for maintaining the piston fluid-tight within the working cylinder of a steam or other motive-power engine.

The object of the invention is to provide a simple, efficient and durable expansible metallic packing adapted to prevent leakage of the motive-power fluid as the piston is moved back and forth within the working cylinder.

The invention will first be hereinafter more particularly described, with reference to the accompanying drawings, which are to be taken as a part of this specification, and then pointed out in the claims at the end of the description.

Figure 1 of said drawings is a longitudinal sectional side elevation of a piston embodying my invention, arranged within the working cylinder of a steam or other engine;

Fig. 2 is a transverse section taken on the line 2—2 of Fig. 1;

Fig. 3 is a side elevation of a hollow conoidal metallic split ring forming a part of my improved metallic packing;

Fig. 4 is a vertical sectional view taken on the line 4—4 of Fig. 3;

Fig. 5 is a perspective view of one of the outer or band rings adapted to fit over or against one of the inclined sides of the conoidal ring;

Fig. 6 is a detail perspective view of parts illustrating the mode of sealing the joint or opening formed by the split in the band ring;

Fig. 7 is a similar view illustrating a modification of the sealing means shown in Fig. 6; and

Fig. 8 is a detail plan view of a portion of the piston head shown in Fig. 1.

Referring to said drawings, in which the

same reference letters are used to denote corresponding parts in different views, the letter A may denote the head of a piston, which is shown fitted within a cylinder B, and provided with a reduced section integral with or secured to a disk a^1 so as to provide an annular recess to receive and retain metallic packing whereby leakage of the motive-power fluid is prevented; said recess being of the desired width to receive and confine between the piston head proper and the disk a^1 one or more double conoidal rings and a plurality of band rings, preferably two double conoidal rings being employed each having a pair of band rings fitted thereon, as shown in Fig. 1 of the drawings. The double conoidal ring D consists preferably of rolled spring steel adapted to secure the desired resiliency, though other suitable metal may be used. The ring D is V-shaped in cross section and provided with slots d in opposite walls thereof arranged in staggered relation and adapted to compensate for any lateral expansion or contraction due to heating or cooling and to facilitate assembling, the ring being split, as at d^1 , to adapt it to expand or contract in diameter. Two outer or band rings E and F are fitted around the ring D, one upon each inclined side thereof, each being split, as shown, to adapt it to expand or contract, and each has one side thereof cut or machined off, as at e , to adapt it to fit closely against the correspondingly inclined side wall of the ring D, while the outer sides thereof are plain or smooth to adapt them to fit closely against the side walls of the recess in the piston head. In order to prevent rotary movement of one ring independently of the other and to insure an absolutely leak-proof joint, one (or both) of the rings E and F may be held in a fixed position relatively to the ring D by means of a flange or projection f on the ring D engaging an oblong recess f^1 in the adjacent band ring extending from the inner edge thereof substantially at right angles to the circle described by the ring, so as to form an interlocking connection, which will permit the rings to be easily assembled or disconnected permitting sidewise movement and radial expansion and contraction of the outer ring and at the same time render it impossible for the splits in the adjoining rings to be thrown into alignment.

so as to cause leakage of the motive-fluid, which might otherwise occur. In order to further provide against leakage, recesses e^1 may be provided in the adjacent end-portions formed by the split in the band rings E and F, as shown in Fig. 6, to receive a segment or sealing plate G, bridging the space or opening formed by the split, so as to seal the joint without interfering with the expansion or contraction of the ring. Instead of a segmental plate fitting a correspondingly shaped recess, as shown in Figs. 6 and 8, the recess may encircle or extend entirely around the edge of the band ring and a split seal ring of equal length with the band ring may be used to seal the joint between the end portions of the band ring where the split occurs; as indicated by the fragmentary view Fig. 7.

20 When two or more double conoidal rings are used, it is preferable to provide a seal for the split in the two outer rings only, as shown in Fig. 8, as the two center rings expand equally against the cylinder walls and are themselves locked to the conoidal rings so as to form a permanent seal.

The advantages of my improved metallic packing will be apparent to those familiar with the art. The peculiar formation of the double conoidal ring and its resiliency adapt it when placed within the V-shaped recess formed by the overlying juxtaposed band rings and compressed therebetween to expand laterally and circumferentially, exerting a pressure that tends to open or expand the band rings so as to hold the peripheral portions thereof in close contact with the interior wall of the cylinder and also to force them against the side walls of the recess in the piston head, thus rendering the packing thoroughly effective in preserving the piston fluid-tight within the cylinder while permitting the several rings to be readily assembled and taken apart, and any wear which takes place between the rings and cylinder or between the rings themselves will be automatically taken up and at the same time a fluid-tight connection will be

maintained, and the wear on the several parts reduced and rendered uniform. The 50 hollow or V-shaped form of the double conoidal ring also combines lightness with strength and its resiliency is increased by the slots arranged in staggered relation in its outer inclined walls.

Having thus described my invention what I claim as new and desire to secure by Letters Patent of the United States is:—

1. A packing for pistons comprising a resilient double conoidal split ring provided 60 with open-ended slots arranged in staggered relation in the conoidal walls thereof, the open ends of the slots being at the base of the cone, together with outer split rings fitting upon the conoidal surfaces of the first 65 mentioned ring.

2. In a piston packing, a double conoidal packing ring having open ended slots in both of its inclined walls to compensate for lateral expansion or contraction.

3. A piston packing comprising an inner double conoidal split ring having spaced open-ended slots in each inclined wall, to compensate for any lateral expansion or contraction, the open ends of the slots being 75 at the base of the cone, and a pair of substantially conoidal split outer rings fitting upon and overlapping the inclined surfaces of said inner ring and having an interlocking connection therewith permitting radial 80 movement but preventing rotary movement of one ring upon another.

4. A piston packing comprising a resilient double conoidal contractible split ring having open-ended slots in its inclined walls 85 extending from an intermediate point to the base of the cone, and outer expansible split rings fitting upon the conoidal surfaces of the first mentioned ring.

In testimony whereof I affix my signature 90 in the presence of two witnesses.

THOMAS G. SAXTON.
